UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

DESIGN FOR A CASING FOR PENDENT ELECTRIC SWITCHES.

46,130.

Specification for Design.

Patented July 21, 1914.

Application filed May 31, 1912. Serial No. 700,848. Term of patent 14 years.

To all whom it may concern:

Be it known that I, CHARLES J. KLEIN, a citizen of the United States, residing at Milwaukee, in the county of Milwaukee and State of Wisconsin, have invented a new, original, and ornamental Design for the Casing for Pendent Electric Switches, of which the following is a specification, reference being had to the accompanying drawing, forming part thereof.

Figure 1 is an elevation of a pendent switch casing, showing my new design. Fig. 2 is a bottom plan view thereof.

I claim:

The ornamental design for a casing for pendent electric switches, as shown.

CHARLES J. KLEIN.
